SUCTION PICK-UP HEAD

Richard L. Swartz, Columbia, S.C., assignor to Universal Business Machines, Inc., Columbia, S.C., a corporation of South Carolina

Filed Sept. 30, 1957, Ser. No. 687,160

6 Claims. (Cl. 294—64)

This invention relates to a device for picking up documents, one at a time, from the top of a stack of documents. The term "documents" as used herein refers to sheet-like material or articles generally, such as checks, vouchers, receipts, paper money, and the like.

While not limited to such use, this invention is especially useful in document-sorting machines of the type disclosed in United States Letters Patent No. 2,668,706 issued to Le Roy J. Benson, and a specific application of the invention to a sorting machine of this type is disclosed in my copending application entitled "Suction-Head Document Feeder" filed jointly with William D. Highsmith.

An object of the invention is to devise a pick-up head involving a suction nozzle for lifting the uppermost document from a stack under suction action.

A further object of the invention is to devise a pick-up head of the suction type which not only lifts the document from the stack, but buckles the document under suction action to aid in separating the top document from the next lower document.

A specific embodiment of the invention is illustrated in the accompanying drawing in which:

Figure 1 is a side elevational view of the entire pick-up head or device;

Figure 2 is a front elevational view of the lower end of the suction nozzle on a considerably enlarged scale with respect to Figure 1;

Figure 3 is a bottom view of the enlarged head on the suction nozzle; and

Figure 4 is a view of the enlarged head on the suction nozzle as seen from the right of Figure 3.

Referring to the drawing, the section head is formed of a suction tube having a horizontal shank section 1 and a nozzle section 2 extending downwardly from section 1. The lower end of nozzle section 2 is provided with an enlarged head 3 which is shown substantially full size in Figure 1 and is shown on a larger scale and in greater detail in Figures 2 to 4.

The shank section 1 is provided for the purpose of mounting the pick-up head for relative movement with respect to a stack of documents so that the tip of the nozzle may be moved into contact with the uppermost document to remove the document from the stack and then moved to transfer the document to a location adjacent to the stack. Such mounting arrangement forms no part of the present invention, but a suitable arrangement is disclosed in my copending application referred to above.

The tip or head of the nozzle is enlarged with respect to the tube section 2 for the purpose of having the nozzle cover a relatively large area of the document and thereby spread the air stream over a larger area to increase the pull on the document. The enlarged head or tip of the nozzle is formed of a cup-shaped part 3 mounted at the lower end of tube section 2 and having an enlarged bore 3a which forms an enlarged extension of the bore in tube section 2. The open end of the member 3 is covered by

2

a flat plate 4, which plate is provided with an aperture 4a displaced from the center of the plate towards one side of the plate, in the manner shown in Figure 3. It is preferred that the aperture 4a shall be an elongated aperture with its major axis arranged parallel with the axis of the shank portion 1, but displaced to one side of the common plane containing the axes of tube sections 1 and 2. Thus, in Figure 3 the broken line 1a represents the common plane containing the axes of tube sections 1 and 2, and the broken line 4a' represents the major axis of the aperture 4a. The outer face of plate 4, in the area 4b in Figure 3, and located between the lower edge of aperture 4a and the bottom edge portion of the plate, is smoothly rounded as shown in Fig. 4 to provide a rounded surface for engaging the top of the stack with the nozzle tilted at different angles. For greatest pick-up effect, the nozzle would be lowered into pick-up position with the lower face of the head 3 parallel with the top of the stack, and this would be the position of operation to pick up heavy paper. For use in connection with relatively thin paper, the nozzle would be lowered into pick-up position with the tube section 2 tilted about the axis of shank section 1 so that the rounded portion 4b is lowermost and would engage the top of the stack. The initial amount of pull on the top document can be varied by varying the angle of tilt of the nozzle, thereby varying the angle of the bottom face of plate 4 with respect to the top of the stack.

For the purpose of aiding in the separation of the top document from the next lower one, the plate 4 is milled or otherwise formed to provide a shallow groove 4c covering substantially all of the area above the aperture 4a as seen in Figure 3 and extending at right angles to the major axis of the aperture. It will be understood that as the suction of the nozzle pulls the top document into contact with the lower face of plate 4, the document is buckled upwardly into contact with the cylindrically curved surface of the shallow groove 4c. This buckling action serves to ensure positive separation of the top document from the next lower one, especially in the case of heavy paper stock.

For use in connection with light paper stock, a second groove 4d with a cylindrically curved bottom is formed at the bottom of the groove 4c. As shown in Figure 2, this groove 4d has a much shorter radius of curvature than the shallow groove 4c and is of considerably smaller width than the groove 4c. This will result in greater buckling of thin paper into the groove 4d.

For the purpose of further aiding the pick-up and buckling action, a third groove 4e is formed at the bottom of groove 4d. As shown in Figures 2 and 3, this groove is relatively narrow with respect to the other grooves and is provided with parallel sides and a sloping bottom which increases in depth from substantially zero near the outer edge of the plate 4 to substantially the full depth of the plate at the edge of aperture 4a. In Figure 4 the dotted line 4c' and 4d' represent the bottoms of grooves 4c and 4d, respectively, while the slanting line 4c' represents the bottom of groove 4c.

60 What I claim is:

1. A suction pick-up head comprising a tube, a flat wall member secured to and lying across the mouth of said tube and having an aperture formed therein, said wall having a shallow cylindrical groove no wider than the aperture formed in the outer face thereof extending from the outer edge of said wall, and terminating at the nearest rim portion of the aperture, a second cylindrical groove formed in the outer face of said flat wall at the bottom of said shallow cylindrical groove and having a shorter radius of curvature than said shallow groove and coextensive therewith.

2. A pick-up head comprising a tube formed of a

shank section and a nozzle section extending at right angles to the shank section, an enlarged head at the end of said nozzle section and having a rigid flat end wall having an aperture formed therein adjacent one side of said head, said aperture being displaced to one side of the common plane containing the axes of said shank section and said nozzle section, and said end wall having a shallow cylindrical groove no wider than said aperture formed in the outer face thereof at right angles to said plane extending from the opposite side of said head and 10 terminating at the rim of the aperture closest to said opposite side, said end wall being provided with a second cylindrical groove formed in the outer face thereof at the bottom of said shallow cylindrical groove and having a shorter radius of curvature than said shallow groove 15 and coextensive therewith.

3. A pick-up head according to claim 1 wherein said flat wall is provided with a narrow parallel-sided groove formed in the outer face thereof at the bottom of said second cylindrical groove and increasing in depth from 20 near the outer edge of said wall to the rim of said aperture.

4. A pick-up head according to claim 2 wherein said end wall is provided with a narrow parallel-sided groove formed in the outer face thereof at the bottom of said 25

second cylindrical groove and increasing in depth from near the edge of said head to the rim of said aperture.

5. A pick-up head according to claim 2 wherein said aperture is an elongated aperture having its major axis parallel with the axis of said shank section.

6. A pick-up head according to claim 5 wherein the outer edge portion of the face of said enlarged head is smoothly rounded from the outer edge of said elongated aperture to the outer peripheral edge of said head.
